COLLAPSIBLE TUBE SQUEEZER

John Lovrich, Piermont, N. Y.

Application February 12, 1935, Serial No. 6,234

2 Claims. (Cl. 221—60)

The present invention relates to new and useful improvements in collapsible tube squeezers and has for its primary object to provide, in a manner as hereinafter set forth, a device of this character comprising a novel construction, combination and arrangement of parts through the medium of which the contents of a collapsible tube may be conveniently ejected as desired in a neat, sanitary and otherwise generally satisfactory manner.

Another important object of the invention is to provide a squeezing device of the aforementioned character which may be expeditiously connected or attached to the tube and removed therefrom when said tube has been emptied.

Another important object of the invention is to provide a squeezer of the character described which embodies a construction which is such that substantially all of the contents of the tube may be ejected, thus materially reducing or eliminating waste.

Other objects of the invention are to provide a collapsible tube squeezer which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of an embodiment of the invention, showing the same attached to the closed end or bottom of a collapsible tube.

Figure 2 is a view in vertical section through the invention, showing how the device is attached to the collapsible tube.

Figure 3 is a vertical sectional view, showing the invention substantially at the beginning of the winding or squeezing operation.

Figure 4 is a vertical sectional view, showing the invention after the squeezing operation has progressed as compared with the illustration in Figure 3.

Figure 5 is a plan view of the invention.

Figure 6 is a front elevational view.

Figure 7 is a detail view of the blank from which the plate and slotted ears or arms are formed.

Figure 8 is a detail view in perspective of the winding key.

Referring now to the drawings in detail, it will be seen that the embodiment of the invention

which has been illustrated comprises an outwardly or rearwardly curved finger plate 1 of suitable resilient metal which is engageable with one side of the collapsible tube 2. At its lower end, the finger plate 1 is curved forwardly and then upwardly, as at 3, and terminates in a resilient pressure plate 4 which is engageable by the thumb of the hand in which the device is being held, as suggested in Figure 1 of the drawings. The pressure plate 4 terminates in an outwardly curved upper end portion 5 to prevent the thumb from slipping therefrom.

Formed integrally with the side edges of the finger plate 1 are ears 6 which project forwardly beyond the pressure plate 4. The ears 6 have formed therein slots 7 in which a removable winding key 8 is operable. As illustrated to advantage in Figure 8 of the drawings, the shank of the winding key 8 has formed therein a slot 9 for the reception of the usual flat, closed end of the collapsible tube 2. The bifurcations of the key 8 are rounded on their free ends, as at 10, to facilitate slipping said key on the tube. The key 8 further includes an operating handle 11.

It is thought that the manner of using the device will be readily apparent from a consideration of the foregoing. The winding key 8 is engaged in the slots 7 of the ears 6 between the finger plate 1 and the pressure plate 4. The substantially flat closed end of the collapsible tube 2 is then engaged in the slot 9 of the key 8 in the manner shown to advantage in Figure 2 of the drawings. This operation may be conveniently accomplished by slipping the bifurcated key 8 over the closed end of the tube as said key is inserted in the device. With the squeezer held in one hand, as suggested in Figure 1 of the drawings, the key 8 is then rotated with the other hand through the medium of the handle 11 in a manner to wind the collapsible tube 2 thereon, as suggested in Figures 3 and 4 of the drawings. As the tube is wound on the key 8 the pressure of the plate 4 thereagainst retains said key closely adjacent the plate 1 in the slots 7 for forcing the contents from said tube. The slots 7 permit the key 8 to shift sufficiently to compensate for the increase in the diameter of the roll of tube on said key 8. The resiliency of the metal from which the device is formed will permit the portions 1 and 4 to spread sufficiently to accommodate the roll as it increases in size.

It is believed that the many advantages of a collapsible tube squeezer constructed in accordance with the present invention will be readily understood, and although a preferred embodiment

of the invention is as illustrated and described, it is to be understood that changes in the details of construction and in the combination and arrangement of parts may be resorted to which will fall within the scope of the invention as claimed.

What is claimed is:—

1. A collapsible tube squeezer comprising a curved finger plate engageable with one side of the tube, opposed ears projecting from the finger plate, said ears having slots therein, the finger plate including a forwardly and upwardly curved lower end portion terminating in a resilient pressure plate, and a removable key rotatably mounted in the slots and slideable longitudinally of the slots and transversely of the longitudinal axis of the key, said key being adapted for connection with the tube for winding said tube, the pressure plate

being engageable with the portion of the tube which is wound on the key.

2. A collapsible tube squeezer comprising an elongated channel member having opposed ears projecting from the edges of one side of the member across the ends thereof and having longitudinal slots formed therein, and a removable winding key rotatably mounted in the slots and movable longitudinally of the slots and transversely of the longitudinal axis of the key and adapted for connection with the tube for winding said tube, one side of the member being curved upwardly and outwardly to form a guide and the other side being shorter and curved upwardly and outwardly to form a pressure plate, the member being formed of resilient material.

JOHN LOVRICH.
